UNITED STATES PATENT OFFICE

146,540

DESIGN FOR A STEIN

Joseph Gmeindl, Milwaukee, Wis.

Application January 16, 1946, Serial No. 125,592

Term of patent 14 years

(CL. D44—9)

To all whom it may concern:

Be it known that I, Joseph Gmeindl, a citizen of the United States, residing at Milwaukee, in the county of Milwaukee and State of Wisconsin, have invented a new, original, and ornamental Design for a Stein, of which the following is a specification, reference being had to the accompanying drawings forming a part hereof.

In the drawings:

Figure 1 is a front perspective view of a stein, showing my new design;

Figure 2 is a side perspective view of the stein from the left of Figure 1;

Figure 3 is a side perspective view thereof taken from the right of Figure 1; and

Figure 4 is a rear perspective view.

I claim:

The ornamental design for a stein, substantially as shown.

JOSEPH GMEINDL.
